US00D892506S

(12) **United States Design Patent** (10) **Patent No.:** **US D892,506 S**
Okai et al. (45) **Date of Patent:** **** Aug. 11, 2020**

(54) **ELECTRIC TOOTHBRUSH HANDLE**(71) Applicant: **Colgate-Palmolive Company**, New York, NY (US)(72) Inventors: **Takahide Okai**, Highland Park, NJ (US); **Brian Bloch**, Hillsborough, NJ (US); **Brett Newman**, San Francisco, CA (US); **Kyle Swen**, San Carlos, CA (US); **Francois Dransart**, San Francisco, CA (US); **Carly Byungyeon Kim**, San Francisco, CA (US)(73) Assignee: **Colgate-Palmolive Company**, New York, NY (US)(***) Term: **15 Years**(21) Appl. No.: **29/673,742**(22) Filed: **Dec. 18, 2018**(51) **LOC (12) Cl. .... 28-03**(52) **U.S. Cl.**USPC ..... **D4/101**(58) **Field of Classification Search**

USPC D4/100, 101, 102, 104, 105, 106, 107, D4/108, 109, 110, 111, 112, 113, 114, D4/115; 15/167.1; D24/146

CPC A46B 2200/1066; A46B 9/04; A46B 15/0081; A61C 17/222; A61C 17/24; A61C 17/26

See application file for complete search history.
